UNITED STATES PATENT OFFICE.

IRA ABBOTT, OF WYANDOTTE, MICHIGAN.

STEAM-TURBINE.

No. 854,447.

Specification of Letters Patent.

Patented May 21, 1907.

Application filed April 23, 1906. Serial No. 313,111.

To all whom it may concern:

Be it known that I, IRA ABBOTT, a citizen of the United States of America, residing at Wyandotte, in the county of Wayne and 5 State of Michigan, have invented certain new and useful Improvements in Steam-Turbines, of which the following is a specification, reference being had therein to the accompanying drawings.

10 This invention relates to improvements in steam turbines and its object is to so apply the steam to the rotary piston that each pocket therein will receive and discharge steam a number of times during each revolution of the piston and to so construct the piston that it will simultaneously close all of 15 the steam inlets to increase the impact of the steam by giving thereto a pulsation.

A further object of the invention is to increase the economy and efficiency of the engine by forming the rotary piston with a series of circumferential separated rows of steam pockets and providing cross-over passages to conduct the steam from one to the 25 other of said rows; and also to so form each pocket as to aid in the discharge of the steam therefrom and lessen the friction of said steam upon the cylinder.

It is also an object of the invention to provide means for automatically governing the 30 speed of the engine by restricting or increasing the flow of steam near its several points of entry into the cylinder so that the speed of the engine will be immediately affected by such manipulation and to provide a motor of 35 the class described having the several advantages of the particular construction, arrangement and combination of parts, all as hereinafter more fully described, reference 40 being had to the accompanying drawings, in which

Figure 1, is a longitudinal vertical section of a device embodying the invention; Fig. 2, a transverse vertical section of the same on 45 the line $x-x$ of Fig. 1; Fig. 3, an end elevation; and Fig. 4, a sectional detail of the cylinder showing the ports and passages therein.

As shown in the drawings 1 is a suitable base to which the horizontally extending 50 cylinder 2 is secured, said cylinder being provided with heads 3 bolted to the ends of the cylinder to close the same and having axial roller bearings 4 for a drive shaft 5. Securely keyed upon the shaft within the cylinder 55 is a rotary piston 6 consisting of a cylindrical drum 7 upon which are slipped a series

of rings 8 provided with steam pockets 9 each formed with a deep and slightly undercut forward end and shallow rear end, said pockets being spaced so as to leave dividing webs 10 between them each having an outer face 11 to engage the inner surface of the cylinder. These pocket rings are separated by spacing rings 12 forming walls between the rows of pockets to prevent the steam from 60 passing from one row to the next and each ring 12 is formed with a broadened outer edge 13 forming an extended surface to engage the inner surface of the cylinder and more effectually prevent the steam from 65 passing. The angles 14 thus formed at the outer side of the pockets by the laterally extending portions of the broadened edges 13, are rounded so that when the steam is injected into one of the pockets and strikes the 70 walls formed by the spacing rings, it will be deflected inward by the rounding inwardly projecting edges toward the exhaust passage 15 opening from the center of the pocket and will also tend to prevent the steam from 75 pressing outward into strong frictional contact with the surface of the cylinder. The pocket rings are secured in place by bolts 16 passing through said rings and drum and the spacing rings 12 are held by bolts or rods 80 passing therethrough and through the pocket rings longitudinally of the piston.

17 is a steam supply pipe opening into a circumferential steam passage 18 formed at one end of the cylinder, and communicating 90 with this passage, are a number of inlet openings forming jet openings 19 cut in the cylinder at an angle to the radii thereof in the direction of the rotating of the piston and opening into the first row of pockets at one 95 end of the piston. The jet openings are preferably of such a number and so spaced around the cylinder that there will be one for every alternate pocket and when the piston is turned so that the face 11 of one of the 100 webs covers one of these openings all will be closed, thus cutting off the steam from the piston between the pockets for a very short space of time and causing a pulsation or intermittent application of power to the piston. 105

While steam is passing into one of the pockets from one of the jet openings, the steam just previously emitted from said opening into the next pocket is escaping therefrom through a cross-over exhaust passage 20 formed in the cylinder into one of the pockets of the next row on the piston. Simi-

lar cross-over passages are provided to conduct the steam from one row of pockets to the next throughout the length of the piston and thus the steam entering a pocket of the 5 first row escapes therefrom into the next row before the next jet is reached and travels in this manner longitudinally of the piston from row to row spirally around said piston and finally escapes into a circumferential exhaust 10 passage 21 formed in the cylinder at its rear end. In the construction shown, the piston is given an impetus as each pocket passes each jet, the pockets being filled and emptied of steam six times during each revolution.

15 The speed of the engine is automatically governed by forming the cylinder with a longitudinal hole at the point where each jet opening opens into the steam passage and securing in each of these holes a rotatable tubular valve 22 having a stem 23 at one end 20 extending outward through a stuffing box 24 carried by a plug screwed into the end of the hole.

Upon the outer ends of the stems are secured pinions 25 in mesh with a large gear 26 25 loosely mounted upon an extended portion of the bearing on the cylinder head.

27 is any suitable governor receiving motion from the engine shaft and a rod 28 operated by said governor is attached at its opposite end to said gear 26 so that as the speed 30 of the engine increases and the governor is operated thereby to lift the rod, the gear will be turned a short distance and all of the 35 valves will be simultaneously rotated thereby. Openings 29 in these valves form a part of the steam passage 18 to permit the steam to pass freely therethrough and into their interior, escaping therefrom into the jets 40 through ports 30 in the valves. Small ports 31 are preferably provided in these valves opposite the third and fifth rows of pockets to admit steam to said pockets through small 45 jet openings 32 in the cylinder and supply live steam to mix with the partially expanded steam which was admitted at the forward end of a cylinder. Water of condensation is drawn off through a valve 33 at the bottom 50 of the cylinder before starting the engine.

55 Having thus fully described the invention, what I claim is:

1. In a compound steam turbine, the combination with a cylinder, of a rotary piston in said cylinder provided with circumferential rows of steam pockets, a series of tangential jets to eject steam into said pockets arranged at intervals around the piston, and a series of spirally arranged cross-over passages opening at one end in rear of said jets 60 to receive the steam ejected into said row of pockets and opening at their opposite ends into the next row of pockets.

2. In a compound steam turbine, the combination of a rotary piston having a series of 65 separated rows of undercut steam pockets, and

a cylinder formed with a series of tangential inlet openings arranged at intervals around the cylinder near one end to admit steam to the first row of pockets and having a series of spirally arranged cross-over passages 70 opening at one end into the first row of pockets between the inlet openings and at their opposite ends into the next row of pockets and spirally arranged cross-over passages 75 communicating with each succeeding row of pockets between the inlet ends of said passages opening into said rows.

3. In a steam turbine, the combination of a cylinder formed with a series of jet openings arranged at intervals around the cylinder and a series of exhaust passages opening between the jet openings, and a rotary piston in said cylinder provided with pockets equal in number to the number of jet and exhaust 80 openings and formed with deep undercut 85 forward ends and shallow rear ends and divided from each other by webs having extended outer faces to engage the surface of the cylinder and simultaneously close the jet openings.

4. In a steam turbine, the combination of a cylinder provided with jet openings and cross-over passages opening between the jet openings, and a piston consisting of a drum, a series of rings formed with steam pockets 90 having deep and slightly undercut forward ends and shallow rear ends, secured on said drum, and spacing rings forming dividing walls between said pocket rings and formed with broadened outer edges forming laterally extending deflecting portions in the outer angles of said pockets.

5. In a steam turbine, the combination of a cylinder formed with a circumferential steam passage, holes cutting said passage longitudinally of the cylinder and forming valve seats and jet openings leading from said holes, tubular valves in said holes, a rotary piston in said cylinder, an outwardly extending valve stem on each of said valves, a 105 pinion secured upon each stem, a gear mounted concentric with the axis of the cylinder to engage and simultaneously turn the pinions, and means controlled by the speed 110 of the engine for turning said gear.

6. In a steam turbine, the combination of a cylinder formed with a circumferential steam passage near one end, a circumferential exhaust passage near the opposite end, longitudinal holes cutting the steam passage 120 at intervals around the cylinder, jet openings leading from said holes into the cylinder, and cross-over passages; a rotary piston in said cylinder formed with circumferential rows of steam pockets separated by walls 125 and communicating through the cross-over passages; rotary valves in the holes in the cylinder; and means for turning said valves simultaneously.

7. In a steam turbine, the combination of 130

- a cylinder formed with a circumferential steam passage at one end, holes cutting said passage and extending longitudinally of the cylinder, jet openings leading diagonally inward from said holes and cross-over passages arranged at intervals around the cylinder throughout its length; heads on the cylinder formed with axial bearings; a shaft in said bearings; a rotary piston on said shaft consisting of a drum, rings secured upon said drum provided with steam pockets separated by webs, and spacing rings between the pocket rings formed with laterally extending outer edges; tubular valves in the longitudinal holes in the cylinder having valve stems 15 at one end; plugs to close the outer ends of said holes and provided with stuffing boxes through which the stems extend; pinions on the said stems; a gear turning upon the axis of the cylinder and engaging all of the pinions; 20 a governor; and a rod connecting said governor and gear.
- In testimony whereof I affix my signature in presence of two witnesses.

IRA ABBOTT.
